UNITED STATES PATENT OFFICE.

ROBERT S. HICKISH, OF TUCKAHOE, NEW YORK, ASSIGNOR, BY MESNE ASSIGNMENTS,
TO EDWARD T. POWELL, OF COLUMBUS, OHIO.

DESIGN FOR A FIRE-EXTINGUISHER CASING.

47,300.

Specification for Design.

Patented May 4, 1915.

Application filed March 4, 1914. Serial No. 822,527. Term of patent 14 years.

To all whom it may concern:

Be it known that I, ROBERT S. HICKISH, a citizen of the United States, residing at Tuckahoe, in the county of Westchester and State of New York, have invented a new, original, and ornamental Design for a Fire-Extinguisher Casing, of which the following is a specification, reference being had to the accompanying drawing, forming part thereof.

The figure is a perspective view of a fire extinguisher showing my improved design.

I claim:

The ornamental design for a fire extinguisher casing as shown.

ROBERT S. HICKISH.

Witnesses:

A. G. WILBUR,
B. J. HUERLANDER.
